ELECTRON BEAM DEFLECTION
MULTIVIBRATOR CIRCUITS

Glyn A. Neff, Pasadena, Calif., assignor, by mesne assignments, to Consolidated Electrodynamics Corporation, Pasadena, Calif., a corporation of California

Application July 30, 1954, Serial No. 446,900

1 Claim. (Cl. 250—27)

This invention relates to multivibrator circuits, and more particularly to an improved multivibrator circuit including a beam deflection type electron tube.

Multivibrator circuits, such as the Eccles-Jordan multivibrator circuit, have been employed extensively in electronic equipment as relaxation oscillators, switching circuits, gating circuits, and the like. As is well known, a multivibrator circuit has two conditions of operation which are alternately assumed.

In some instances the circuitry is arranged so that the multivibrator is bi-stable, in which case one condition of operation is maintained until the circuit is forcibly caused to assume its other condition of operation. In other instances, the circuitry of a multivibrator is arranged to be mono-stable, in which case the circuit remains in a stable condition of operation until forcibly caused to assume another condition of operation, and after a predetermined interval depending upon the time constants of the circuit, returns to its stable condition. In addition, multivibrators are sometimes arranged to be free-running, in which case the two conditions of operation are alternately assumed at a rate which is dependent upon the time constants of the circuit alone. Therefore, in accordance with the above, the word "multivibrator" as used herein is intended to mean a circuit which is adapted to have two conditions of operation alternately assumed, and which may be either bi-stable, mono-stable, or free running.

In contrast to conventional multivibrator circuits which normally employ a pair of electron tubes, each of which has a separate electron beam, the multivibrator of my present invention includes a beam deflection type electron tube having a single cathode, a pair of anodes and means for deflecting an electron beam from the single cathode toward either one of the anodes.

In one embodiment a voltage is derived which is a function of the current flowing to at least one of the anodes, and the derived voltage is applied to the deflecting means whereby an electron beam from the cathode is deflected toward a first one of the anodes in a first condition of operation and deflected toward the other of the anodes in another condition of operation.

A better understanding of my invention may be had upon a reading of the following detailed description when taken in conjunction with the drawings, in which:

Fig. 1 is a schematic circuit diagram of a bi-stable multivibrator;

Fig. 2 is a schematic circuit diagram of a mono-stable multivibrator; and

Fig. 3 is a schematic circuit diagram of a free-running multivibrator.

The bi-stable multivibrator of Fig. 1 includes a beam deflection type electron tube 4 having a cathode 5, a control electrode 6, a shield electrode 7, an accelerator electrode 8, a left-hand deflector electrode 9, a right-hand deflector electrode 10, a left-hand anode 11, and a right-hand anode 12.

Assuming that the bi-stable circuit of Fig. 1 is in the

2

condition of operation where an electron beam from the cathode 5 is directed toward the right-hand anode 12, and a negative going triggering pulse is applied to the control electrode 6 via a terminal 13, the electron beam flowing to the right-hand anode 12 will be momentarily decreased. This causes the potential at the right-hand anode 12 to rise due to the decrease in the voltage drop across the load impedance 14.

The rise in potential at the anode 12 of the electron tube 4 is coupled to the left-hand deflector electrode 9 via a coupling capacitance 15 and a resistance 16. The increase in potential at the deflector electrode 9 attracts the electron beam from the cathode 5 toward a left-hand anode 11. This causes the potential at the left-hand anode 11 to drop due to the increased voltage drop across the load impedance 17.

The decrease in potential at the left-hand anode 11 is coupled to the right-hand deflector electrode 10 via a coupling capacitance 18 and a resistance 19. The decrease in the potential at the deflector electrode 10 tends to release the electron beam from being attracted toward the right-hand anode 12. This action is cumulative until substantially all of the electron beam from the cathode 5 is directed toward the left-hand anode 11 and the circuit achieves a stable condition of operation.

In like manner, assuming the electron beam from the cathode 5 is directed toward the left-hand anode 11, and a negative going triggering pulse is applied to the control electrode 6 via the terminal 13, the electron beam is momentarily decreased, thereby causing the potential at the left-hand anode 11 to rise. The rise in potential is coupled to the right-hand deflector electrode 10, thereby tending to attract the electron beam toward the right-hand anode 12. As increasing amounts of electrons flow to the anode 12, the potential at the anode 12 drops and the drop in potential, when coupled to the left-hand deflector electrode 9, tends to release the electron beam from being attracted toward the left-hand anode 11. Again the action is cumulative until the circuit achieves a stable condition of operation in which substantially all of the electron beam from the cathode 5 is directed toward the right-hand anode 12. Thus, the circuitry of Fig. 1 functions as a bi-stable multivibrator. In contrast to conventional multivibrators, however, a single electron tube having a single electron beam is employed, which results in a substantial increase in efficiency since only one electron beam need be generated.

The interval required for the multivibrator of Fig. 1 to change from one stable condition of operation to another may be varied by suitable selection of the time constants of the right-hand coupling circuit, including the coupling capacitance 18 and the voltage divider comprising the resistances 19 and 20 along with a suitable selection of the time constants of the left-hand coupling circuit, including the coupling capacitance 15 and the voltage divider comprising the resistances 16 and 23.

Output signals from the bi-stable multivibrator of Fig. 1 may be derived from the circuit in the same manner as from a conventional multivibrator. For example, one way in which complementary waves may be derived is by means of the terminals 21 and 22 which are connected taps on the load impedances 14 and 17.

The electron tube employed in the mono-stable circuit of Fig. 2 is similar to that employed in Fig. 1. Consequently, like reference characters have been used to designate the various elements.

Assuming that the mono-stable multivibrator of Fig. 2 is in its stable condition of operation in which the electron beam from the cathode 5 is directed toward the right-hand anode 12, a positive going triggering pulse applied to the terminal 24 is coupled to the left-hand deflector electrode 9 via a coupling capacitance 25. This causes

the electron beam to be attracted toward the left-hand anode 11 and away from the right-hand anode 12. The resultant decrease in potential at the left-hand anode 11, due to an increase voltage drop across the load impedance 26, is coupled to the right-hand deflector electrode 10 via a coupling capacitance 27. This tends to deflect the electron beam toward the left-hand anode 11. The action is cumulative until the circuit achieves a condition of operation in which substantially all of the electrons of the electron beam from the cathode 5 flow to the left-hand anode 11.

As the charge on the coupling capacitance 27 leaks off, the right-hand deflector electrode tends to assume a potential determined by the voltage divider comprising a resistance 28 and a resistance 29. As this happens, the electron beam is deflected toward the right-hand anode 12 and away from the left-hand anode 11, and as an increasing amount of electrons flow to the right-hand anode 12, the resultant rise in potential at the left-hand anode 11 is coupled to the right-hand deflector electrode 10 via the coupling capacitance 27, thereby tending to cause the electron beam to be further deflected toward the right-hand anode 12.

Thus, the circuitry of Fig. 2 functions as a mono-stable multivibrator, which when forcibly caused to assume its unstable condition by applying a positive going pulse to the terminal 24, will remain in its unstable condition for a time interval dependent in part upon a suitable selection of the time constant of the coupling capacitance 27 and the voltage divider including the resistances 28 and 29.

The electron tube employed in the free-running multivibrator circuit of Fig. 3 may be the same type as that employed in Figs. 1 and 2 and, consequently, like reference characters have been used to designate the various elements.

Assuming that the free-running multivibrator of Fig. 3 has just assumed the condition of operation in which the electron beam from the cathode 5 is directed toward the right-hand anode 12, the drop in potential at the right-hand anode 12, as a result of an increased voltage drop across the load impedance 31, is passed to the left-hand deflector electrode 9 via a capacitance 32. At the same time, an increase in potential at the left-hand anode 11, caused by a decrease in the current flowing through the load impedance 33, is passed to the right-hand deflector electrode 10 via a capacitance 34.

While the capacitance 32 and the capacitance 34 remain charged by the aforementioned changes in potential at the anodes 11 and 12, the electron beam from the cathode 5 will be deflected to the right-hand anode 12. However, as the capacitance 32 discharges through a resistance 35 and the capacitance 34 discharges through a resistance 36, the electron beam tends to swing toward the center, and the current flowing to the left-hand anode 11 increases while the current flowing to the right-hand anode 12 decreases. The resultant drop in potential at the left-hand anode 11 is coupled to the deflector electrode 10 via the capacitance 34, and the resultant rise in potential at the right-hand anode 12 is coupled to the left-hand deflector electrode via the capacitance 32. This action is cumulative until substantially all of the electron beam is deflected to the left-hand anode 11.

Again, as the capacitance 32 and the capacitance 34 discharge via the resistances 35 and 36, the electron beam tends to swing toward the center, thereby causing a rise in the potential at the left-hand anode 11 and a drop in the potential at the right-hand anode 12. As previously noted, this causes a cumulative action which tends to de-

10 flect the electron beam further toward the right-hand anode 12. This action, in which the electron beam is deflected back and forth between the left-hand anode 11 and the right-hand anode 12, takes place at a rate dependent primarily upon the time constants of the left-hand coupling circuit including the capacitance 32 and the resistance 35, and the right-hand coupling circuit including the capacitance 34 and the resistance 36. Thus, the circuit of Fig. 3 functions as a free-running multivibrator.

15 Output signals from the circuit of Fig. 3 may be derived in a manner similar to that employed in a conventional multivibrator circuit. In addition, the free-running multivibrator of Fig. 3 may be synchronized by applying a synchronizing signal as shown in Fig. 1 or 2, or in any manner in which a conventional free-running multivibrator may be synchronized.

20 By interconnecting a plurality of the bi-stable circuits of Fig. 1, a counter may be formed which is capable of counting in binary notation. By inhibiting the operation of certain ones of the bi-stable multivibrators when certain registrations appear in the circuit as a whole, the circuit may be adapted to count in a permuted binary notation, e. g., from zero to nine. One circuit for inhibiting the passage of count pulses from one bi-stable multivibrator to another bi-stable multivibrator is shown in the co-pending United States patent application, filed May 12, 1954, Serial No. 429,353, in the names of Robert M. Strassner and Everett G. Shover, and entitled "Signal Transfer Circuits."

25 One type of electron tube which may be used in each of the circuits of Figs. 1, 2 and 3 is the type 6AR8 sheet-beam deflector tube, which was originally developed for use as a color television synchronous detector. In some applications it may be possible to omit one or more of the electrodes 6, 7 and 8.

30 I claim:

35 A bi-stable circuit having two conditions of operation, including in combination an electron tube having at least a cathode, a pair of deflector electrodes, and a pair of anodes; a first impedance connected between a first one of the pair of anodes and the cathode; a second impedance connected between another one of the pair of anodes and the cathode; means cross-coupling the anodes and the deflector electrodes comprising a first resistance and a first capacitance connected in parallel between a first one of the pair of anodes and a first one of the pair of deflector electrodes and a second resistance and a second capacitance connected in parallel between the other one of the pair of anodes and the other one of the pair of deflector electrodes; and triggering means coupled to the electron tube for momentarily decreasing the electron flow from the cathode.
